SILHOUETTE MODEL

Donald K. Howard, Cincinnati, George W. Benckenstein, Jr., Deer Park, and Harry L. Porter, Cincinnati, Ohio, assignors to Burton-Rodgers, Inc., a corporation of Ohio

Application July 2 1942, Serial No. 449,442

15 Claims. (Cl. 35—1)

It is the object of our invention to produce a cut-out pattern in a flat sheet and an aeroplane model to be constructed therefrom which gives a correct silhouette of the plane from front, side, rear elevation and plan view. Such models can be furnished at a relatively low cost and when put together according to instructions will serve as study models whereby various styles and makes of aeroplanes can be recognized. The eye quickly fills in the solid outlines from such silhouettes from a knowledge of aeroplane design in general.

Among other objects is the production of cut-out designs from which the correct silhouette models can be made without any pasting or gluing from die cut paper board blanks, and treating the paper board thereafter. The die cutting is thus done through relatively soft board and the treatment may be such as both to harden the board and also give it a waxy surface that facilitates the tight assembly of the parts. The color that is best for use as a silhouette may be applied before the treatment or as a part thereof. Also it is an object to so design the pieces that when cut out from a flat pattern, they will serve when thrust together to lock into each other sufficiently to make the models when completed sturdy enough to be handled, and dropped, without coming to pieces.

The style in general of forming up the pattern parts will necessarily vary with each model, for one reason because it is necessary in order to give a correct silhouette to place a flat piece at every point where the silhouette outlines indicate that the maximum projection of that part should come. Otherwise, while the silhouette might be correct from one point of view, it would not be correct from another.

In the specification that follows and in the drawings, we have shown but one cut-out pattern and model, and in the claims that follow we have pointed out and claimed the novel features incident to the making of such models without particular reference to the one that is shown, because it is illustrative of the invention and not to be taken as an inflexible guide in the production of models which vary, there being certain general features which if followed, will serve to guide those skilled in the art to produce various styles when following the general features of the model illustrated.

In the drawings:

Figure 1 is a plan view of the cut-out piece of paper board.

Fig. 2 is a top plan view of the assembled model.

Fig. 3 is a side elevation of the assembled model.

Fig. 4 is a front elevation of the assembled model.

Fig. 5 is a rear elevation of the assembled model.

Fig. 6 is a detail plan view showing a modified arrangement employed for interlocking wing panel and wing support at the lengthwise axis of the plane model.

Fig. 7 is a section on line 7—7 of Fig. 6.

The cut-out pattern sheet is noted at 1. Within it are a series of shaped pieces which are sufficiently severed by means of die cuts into the sheet of board that they can readily be pushed out of the sheet, ready for assembly. Preferably the cutting die passes entirely through the paper board sheet and the panels stay in place frictionally.

The board used is relatively soft to facilitate die cutting and thereafter the sheet is treated with some suitable composition of waxy material such as paraffin to give it a slight malleability, together with a resin which will harden the board and increase its strength. This treatment may also blacken the board without imparting a shine to it, or the board may be made black in the first place, to facilitate the use thereof as a silhouette. For some purposes the board may be colored or printed.

The wing support member is indicated at 2, on the cut-out pattern. It has two T shaped notches therein, indicated at 2a, and also two slightly rounded projections 2b, 2b and a median large projection 2c. The projections 2b are to indicate the shape in front elevation and rear elevation of the back of the engine nacelles. The central projection 2c constitutes the outline in front and rear elevation of the largest diameter of the fuselage. This indication of fuselage elevation in other models might not be in line with the wing support element and a separate piece is often necessary for indicating the largest fuselage dimension in its proper place lengthwise of the completed model.

In the case wing support 2 is used for interlocking purposes, the projection 2c has slots therein in the form of a cross, as at 2d, and two short slots 2e. Each end of the wing support has a long projection 2f, which projections are to be used as tongues for holding the wings.

The horizontal fuselage piece 3 in this case is in one piece. In other models it may be in sev-

eral pieces. It has a slot $3a$ crosswise thereof at the point of its largest dimension, another slot $3b$ opens at one side of the piece. The piece 3 also has a front lengthwise slot $3c$, and a rear slot $3d$, with staggered tongues $3e$ near its rear terminus.

The vertical motor nacelle pieces are shown at 4 , 4 , and are alike. They have long slots $4a$ therein for sliding over the wing member, and vertical slots $4b$ therein for sliding down over the wing support member, and they have also front end slots in the form of a cross, as indicated at $4c$.

As so far described the first step in construction is to slide the wing support 2 sidewise into the piece 3 , (the horizontal fuselage member) using the side slot $3b$ therein. Next the nacelle members 4 are inserted over the wing supports so that slots $4b$ are thrust down as far as they will go in the vertical portion of slots $2a$. This brings the nacelles to the correct position for the silhouette.

The next piece to be considered is the wing member 5 , which is in one piece, with short front and back slots $5a$ and $5b$ along the center line, front edge slots $5c$ where the engine nacelles are located, and lengthwise slots near the tips of each wing element as at $5d$. The next assembly operation is to bend the wing member at the score lines $5f$ slightly so that it will fit onto the wing support, and thrust the same where slots $5c$ are located, into the slots $4a$ of the motor nacelle pieces 4 , and then force the tongues $2f$ at the ends of the wing supports into the slots $5d$. This operation ties down the wings by the nacelle parts, and ties the nacelle parts to the wing supports, thus locking up the structure. The wing member has a lengthwise short slot $5e$ at the center thereof approximately in line with the end slots.

Since the rounded portion $2c$ of the wing support represents only part of the full circle of the rounded fuselage, it is required to provide a round topped piece 6 , having a T head $6a$, and a slotted body $6b$, which is thrust down through the central wing slot $5e$. The slotted body $6b$ lines up with the vertical portion of the cross in the wing support projection $2c$.

The vertical elements of the fuselage are next put into place. In this case they are in two parts. The front part consists of a piece 7 shaped to the vertical dimensions of the fuselage at the front. It has a long slot $7a$, which is lined up with the short front slot $3c$ of the horizontal fuselage piece 3 . Projecting from the slot $7a$ is a tongue $7b$ which when the piece 7 is thrust over the piece 3 , by intermeshing the slotted portions $7a$ and $3c$ and pushing inwardly, will enter the vertical portion of the slot $2d$. The piece 7 has also a short slot $7c$ which is meshed with the slot $5a$ in the wing member thereby interlocking the wing member by means of the piece 7 with the horizontal member. The tongue $7b$ also engages in the enclosed slot of the piece 6 , thus locking it down.

To complete the front of the fuselage silhouette in the particular model, it is required to provide a set back cabin top which is in the form of a piece 8 , having a slot $8a$ therein which is meshed with the upper short lengthwise slot $7d$ in the fuselage piece 7 , and has tongues $8b$ to enter slots $2e$ in the wing support, thus providing three-dimensional engagement.

The rear portion of the vertical portion of the fuselage is a piece 9 . This piece has a tail portion $9a$, beneath which is an end opening slot $9b$, with a short vertical branch slot $9c$ where the rear rudder support piece will be placed. The piece 9

also has a slot $9d$ which meshes with the long slot $3d$, and whereby the piece 9 is thrust lengthwise over the horizontal piece 3 . The front end of this piece 9 has a notch $9e$ producing a tongue $9f$, which clears the tongue $7b$ when the piece 9 is thrust home, and beneath this piece $7b$ passes through the same slots as the piece $7b$. Above the notch $9e$ is a tongue $9g$ which passes through the same slots but above the tongue $7b$. This arrangement locks up the front end of the vertical structure. Piece 9 also has a slot $9h$ which meshes with the slot $5b$ in the wing producing a side elevation of a projection above the wing level back of the rounded top of member 6 .

When the vertical piece 9 is thrust forward into place the tongues $3e$, near the rear end of the long slot $3d$, engage or are thrust into the slanting slot $9j$.

The tail plane consists of a piece 10 , and a plane support 11 . The plane support 11 is thrust endwise into the slot $9c$, the tail plane piece 10 is then bent, slipped into the slot $9b$, and the long stub tongues $11a$ of the support thrust into the lengthwise slots $10a$ in the piece 10 , in the same way as the main wing tips were thrust over the stub tongues of the main wing supports. The tail plane has a slot $10b$ meshing with slot $9b$ in piece 9 .

This leaves the finishing of the engine nacelles. They are formed primarily of pieces 12 for the horizontal nacelle pieces, which have long slots $12a$ therein for meshing with the lengthwise portions of the slots $4c$. The tongues $12b$ on the pieces 12 , when same are thrust over the pieces 4 will engage in the slots $2a$, thus interlocking the rear ends of the pieces 12 . The front ends of the pieces 12 have projecting tongues $12c$ for silhouette purposes. They also have two opposing short slots $12d$ for the engine silhouette pieces 13 and 14 . The slots $12d$ come into the same plane as vertical portions of the cross slots $4c$. The two pieces 13 and 14 are half round and each has a tongue $13a$ and $14a$ in opposed relationship, and median slots $13b$ and $14b$. When the slots $13b$ and $14b$ are meshed with the slots $12d$, and the pieces 13 and 14 thrust home, the tongues $13a$ and $14a$ will engage in the vertical portions of the cross slots $4c$, thus locking up the front ends of the engine silhouettes.

It may be noted that to locate each piece where it is to intersect another piece that there are intermeshing slots, and that where parts intersect each other, slots and tongues are normally provided for interlocking, so that to the greatest extent possible each of the pieces is used to lock the other pieces serving as keys in this respect.

In making up the silhouette, there must be two pieces in relative arrangement to give the proper front and side elevational dimensions, two pieces at right angles, one fitting into another by means of slots in the two pieces. Wherever the silhouette of a part intersects a third piece, then the inserted slotted member is arranged so that it has tongues which enter this third member. This gives a locking together in three planes, (a) the slotted pieces are locked in lengthwise relation, (b) the inserted piece is locked by the solid portion thereof in a parallel plane at right angles to the slot in the starting piece, and (c) the two pieces are locked in a plane at right angles to the other two planes by engagement of the inserted piece in a cross piece which intersects the silhouette.

In making the wings, thickness is given by pieces located edgewise which pieces have ver-

tical long tongues at their ends to be pressed flush into slots in the tips of the wings. In this one instance the construction does not always permit placing the thickness quite as close to the leading edge of the wings as it may belong.

In making engines, there is usually an intersection of the silhouette with the thickness strip for the wings. This permits the inserted horizontally located piece to have tongues to enter this thickness indicating strip of the wings. Since roundness in front elevation must be indicated, two pieces are used which are slotted into the horizontal element, and have tongues to enter holes, one for each piece, located in the vertically extending piece.

The following is a guide to procedure in forming the dies for cutting out the flat sheets for aeroplane models according to the present invention:

1. Procurement of authentic drawings, measurements and other data to show most standard type of certain make and model of airplane.

2. Drawing up (to scale) the front, side and top elevation of said plane with absolute accuracy, but with regard to the silhouette or outline of the plane only and all projections in each of the three views.

3. Designer then breaks down all three views into interlocking pieces so calculated as to maintain the exact silhouette when the model is seen from any of the standard elevations—top, bottom, front, back or sides. Pieces are so designed as to interlock in at least two dimensions, and in three dimensions wherever possible.

(a) Wing is composed (in most cases) of a properly shaped piece, or pieces, bent to proper dihedral angle on one or more scored lines, and supported by one or more bent or straight wing supports designed to give proper shape from front or rear elevation, held in place with slots in body and wing and corresponding lugs on support.

(b) Body is composed of several pieces interlocking by means of slots at correct positions—in larger types held in place by locks, which fit into slot in opposing piece. Pieces are generally constructed to lock into pieces forming other two elevations.

(c) Tail assembly consists of one or more pieces, bent or straight; in some cases made similar to wing and support, in others as slotted piece inserted in slot in rear of plane.

(d) Motor shapes are designed to show proper size and shape from top and bottom or side elevation. These shapes interlock with each other and are also inserted into slots in wing supports or wing and wing support. Frontal shapes of motors are then shown by means of pieces interlocking with other motor shapes, both horizontal and vertical, in order to act as braces holding all shapes in correct position in all elevations.

Note.—Positions of all slots and locking pieces and methods of joining pieces are varied in each plane to suit the particular problem, keeping the number of pieces, necessary to depict a plane accurately, to the minimum.

4. Hand-cut model of each plane is then made to check whether pieces will assemble properly.

5. Each individual piece of each type of plane is then carefully drawn, with its correct size, shape and slots on a sheet of proper size, so that a cutting die may then be manufactured from this information.

We give the following as a detailed example of proper processing of board after die cutting.

With the die cut sheets ready for treatment we preferably first dehydrate and deaerate the board to avoid foaming during the saturating step. To do this we either bake the board in an oven

5 or preferably we dip the sheets for 30 seconds in a bath of white refined paraffin which is at a temperature of around 290 to 300 degrees F. After thus dipping we remove the board and dip it into a bath of one part "piccolyte" a trade name for hydrocarbon turpene resin and six parts of white refined paraffin. This dipping is for around two minutes and the temperature 10 300 to 325° F. In giving the proportions in the second bath we have allowed for the amount of 15 paraffin which remains in the board after the first dipping so that the saturant bears about the proportions given. The sheets when removed from the second bath are racked to cool and harden, the piccolyte being a self-hardening 20 resin.

The result is a dull surface, which is desirable for silhouette purposes. Also the surface is waxy and the parts slightly malleable so as to impart a good adherent grip to interlocked parts. The 25 board is hard, however, so that the parts do not fray or bend during assembly, and remain stiff and in proper shape permanently when in use as silhouette models. The stiffness facilitates pushing the various panels out of the die cut, 30 treated sheet, including the narrow portions in the several panels which define slots for intermeshing the parts, according to the system of assembly.

The time of immersion of the die-cut sheets is not long enough to fill the slots which separate the panels and impregnation rather than complete saturation is thus ordinarily obtained.

In Figs. 6 and 7 are shown a section and plan respectively of a device frequently used in larger models in order to lock the parts together, where the silhouette is not interfered with. Here the wing panel member has a flat portion 58 and two dihedrally extending portions 58a. The wing support 51 has a projection 51a forming the front elevation view of the third dimension of the fuselage, which projection 51a is slotted and the vertical fuselage panel slotted and thrust down over it. To hold the wing down on the wing support two locks in the form of slotted pieces 52 engage in slots 51b in the member 51a, which slots are directly above the wing central panel 58. The little pieces 52 will thus hold the wing down on the wing support. This device is 40 45 50 55 60 65 70 75 80 85 90 95 100 usable in slightly different forms in larger models to give additional strength without affecting the silhouette.

We are aware that card board has been cut into panels which will fit together to represent self-sustaining figures which will stand on a flat surface, and that it is common to slot two pieces of board and intermesh them at the slotted portions, as is done by us. However, we do not know of any one who has formed a true silhouette by this method, which involves the further problem of abutting surfaces in three dimensions, and working out modes of assembly which will interlock the parts in all three dimensions. Nor has anyone worked out a silhouette of an aeroplane formed of interlocked flat pieces, so far as we are advised, using vertical, horizontal and transverse panels for this purpose to give correct elevational views in a very simply formed set of panels, held in a die cut sheet.

Having thus described our invention, what we

claim as new and desire to secure by Letters Patent is:

1. A cut-out sheet comprising a flat paper board having die cut panels substantially completely severed therefrom, said panels having slots for intermeshing purposes and of an outline to make up a three dimensional figure when removed and intermeshed with each other, the lines of severance thereof having been formed in said board prior to impregnating and the board then impregnated with a hardening substance.

2. A cut-out sheet comprising a flat paper board having die cut panels substantially completely severed therefrom, said panels having slots for intermeshing purposes and of an outline to make up a three dimensional figure when removed and intermeshed with each other, the lines of severance thereof having been formed in said board prior to impregnating and the board then impregnated with a hardening substance and a waxy substance.

3. A cut-out sheet comprising a flat paper board having die cut panels substantially completely severed therefrom, said panels having slots for intermeshing purposes and of an outline to make up a three dimensional figure when removed and intermeshed with each other, the lines of severance thereof having been formed in said board prior to impregnating and the board then impregnated with a hardening substance in the form of a resin and a wax.

4. A cut-out sheet comprising a flat paper board having die cut panels substantially completely severed therefrom, said panels having slots for intermeshing purposes and of an outline to make up a three dimensional figure when removed and intermeshed with each other, the lines of severance thereof having been formed in said board prior to impregnating and the board then impregnated with a hardening substance in the form of a resin and paraffin wax.

5. That method of making up a die-cut paper board sheet in which panels are substantially completely severed therefrom, said panels configured to make up a three dimensional figure when removed and slotted for assembly purposes, which consists in die-cutting the panels in a relatively soft paper board, and then saturating the board with a resinous material which imparts hardness and stiffness to the board.

6. That method of making up a die-cut paper board sheet in which panels are substantially completely severed therefrom, said panels configured to make up a three dimensional figure when removed and slotted for assembly purposes, which consists in die-cutting the panels in a relatively soft paper board, and then saturating the board with a resinous material which imparts hardness and stiffness to the board, said resinous material having a wax incorporated therein.

7. A series of shaped flat panels for forming an aeroplane silhouette, comprising panels for wings and wing supports, the wing supports arranged to define the dihedral angle of the wings, and against which the wings rest substantially throughout, said wing supports completing in silhouette the front elevation of the aeroplane wings, and said wing supports having shallow elongated tongues near their ends, the wings having slots in which said tongues engage the tongues having each a length substantially equal to or less than the thickness of the wing whereby

they do not project substantially above the upper wing surface.

8. A series of shaped flat panels for forming an aeroplane silhouette, comprising panels for wings and wing supports, the wing supports arranged to define the dihedral angle of the wings, and against which the wings rest substantially throughout, said wing supports completing in silhouette the front elevation of the aeroplane wings, and said wing supports having shallow elongated tongues near their ends, the wings having slots in which said tongues engage the tongues having each a length substantially equal to or less than the thickness of the wing whereby they do not project substantially above the upper wing surface, said panels also including panels shaped as the plan and side elevational views of the aeroplane fuselage respectively which panels are slotted to intermesh with each other, and the wing supports arranged to pass through slots in the side elevational panel portions of the fuselage panels.

9. A series of shaped flat panels for forming an aeroplane silhouette, comprising panels for wings and wing supports, the wing supports arranged to define the dihedral angle of the wings, and against which the wings rest, said wing supports completing in silhouette the front elevation of the aeroplane wings, and said wing supports having shallow elongated tongues near their ends, the wings having slots in which said tongues engage the tongues having each a length substantially equal to or less than the thickness of the wing whereby they do not project substantially above the upper wing surface, said panels also including panels shaped as the plan and side elevational views of the aeroplane fuselage respectively which panels are slotted to intermesh with each other, and the wing supports arranged to pass through slots in the side elevational panel portions of the fuselage panels, and engine nacelle panels slotted to intermesh each other normal to each other to provide side and plan views of said nacelle, the vertical or side view panels slotted to intermesh with slotted portions at the front edge of a wing panel, and the horizontal or plan panel of the nacelle having tongues to engage in slots in a wing support.

10. A series of shaped flat panels for forming an aeroplane silhouette comprising wing panels and wing support panels arranged for interlocking with each other, and panels for an engine nacelle, the latter consisting of two panels mutually slotted for intermeshing with each other in normal relation, the horizontal engine nacelle panel having tongues to enter slots in the wing support.

11. A series of shaped flat panels for forming an aeroplane silhouette comprising wing panels and wing support panels arranged for interlocking with each other, and panels for an engine nacelle, the latter consisting of two panels mutually slotted for intermeshing with each other in normal relation, the horizontal engine nacelle panel having tongues to enter slots in the wing support, and the vertical nacelle panel slotted to engage with a wing panel.

12. A series of shaped flat panels for forming an aeroplane silhouette, comprising panels for side and plan elevation of the fuselage, mutually slotted for intermeshing, one of the slots in the respective panels having on its opposed walls tongues in staggered relationship and the other of the panels having a slot arranged to receive said tongues.

13. A series of shaped flat panels for forming an aeroplane fuselage comprising a wing panel, having a portion bent with relation to another portion, a horizontal fuselage panel, a vertical fuselage panel, and a front elevational panel projecting normally to both of the fuselage panels, the wing panel passing through the vertical fuselage panel, and locking panels slotted to engage in slots formed in the front elevational panel at substantially the level of the top face of the wing panel where it intersects the fuselage panel, said locking panels arranged to lie flat on the said adjacent portion of the wing panel.

14. A series of shaped flat panels adapted when intermeshed with each other to form an aeroplane so as to form a three dimensional silhouette of an aeroplane, comprising vertical and horizontal fuselage panels, a wing panel, and a wing support panel, the wing support panel hav-

ing a projection slotted to intermesh with the vertical fuselage panel, and in outline forming the third dimensional view of the fuselage, the wing panel being slotted for passage therethrough of the said projection.

15. A series of shaped flat panels adapted when intermeshed with each other to form a three dimensional silhouette of an aeroplane, some of said panels having mutual slots for intermeshing 10 to form two normal elevational planes, and some of said panels arranged to form intersecting planes in the third dimension, the latter panels some of them having tongue and slot connections with one of the first two planar pieces, and mutual 15 slotted relation to the other of said two planar pieces.

DONALD K. HOWARD.
